(57) **CLAIM**

The ornamental design for a watch, as shown and described.

DESCRIPTION

FIG. 1 is a front perspective view of a watch showing my new design;

FIG. 2 is a right side elevational view thereof;

FIG. 3 is a top plan view thereof;

FIG. 4 is a front elevational view thereof;

FIG. 5 is a left side elevational view thereof; and,

FIG. 6 is a rear elevational view thereof.

The bottom plan view is a mirror image of the top plan view.

The broken-line showing of FIGS. 1 and 4 are used to show portions of the watch that do not form part of the claimed design.
